UNITED STATES PATENT OFFICE.

MILTON L. DODGE, OF NEWBURYPORT, MASSACHUSETTS.

TURN SHOE.

Application filed September 25, 1920. Serial No. 412,780.

To all whom it may concern:

Be it known that I, MILTON L. DODGE, a citizen of the United States, residing at Newburyport, in the county of Essex and

5 State of Massachusetts, have invented new and useful Improvements in Turn Shoes, of which the following is a specification.

This invention has relation to foot wear, and more particularly to turn shoes. The 10 object of the present invention is to produce a shoe which is attractive in appearance, which will preserve its shape, and which is comfortable to the wearer.

Turn shoes require the use of a shank 15 stiffener, and, in accordance with the present invention, this shank stiffener is assembled as a component of a combined counter stiffener and shank piece, which may be introduced into the shoe, during the manufacture 20 thereof, as a separate entity. The counter stiffener is initially molded to desired form, and the shank piece is provided with a shank stiffener, which is preferably made of metal. The shank piece, as I term it, approximates 25 in shape the rear part of an innersole, and it is inserted into the counter stiffener so as to overlap the heel-seat flange thereof to which it is secured. In order that the counter lining may be properly tucked into place, 30 without causing discomfort to the wearer, and requiring an additional element, the rear portion or heel end of the shank piece is split, so that connected upper and lower members are provided between which the 35 lower end of the lining may be introduced and secured.

In the manufacture of a shoe embodying the invention, the combined counter stiffener and shank piece (including the metallic 40 shank stiffener) may be attached in place either prior or subsequent to the turning operation, and in the following specification I shall describe several of the ways in which this may be accomplished.

45 Referring to the accompanying drawings,—

Figures 1 and 2 represents plan and edge views of a shank piece blank.

Figure 3 represents an edge view of the 50 same when split.

Figure 4 represents a similar view of the shank piece with the shank stiffener attached.

Figure 5 shows, in plan view, the under 55 side of the shank piece.

Figure 6 shows, in plan view, the com-

bined counter stiffener and shank piece, ready for insertion in a shoe.

Figure 7 illustrates the same in longitudinal section.

Figures 8 and 9 illustrate the attachment of the combined counter stiffener and shank piece to the innersole of a partially formed shoe, after the same has been lasted and prior to its being turned.

Figure 10 represents a finished shoe, partially in section, and partially in side elevation.

Figure 11 illustrates a partially formed shoe with the counter stiffener and shank 70 piece in place, but initially attached to the sole by only two fastenings.

Figure 12 illustrates the same when finished.

Figure 13 shows the heel end of the sole, 75 with the loose nails which secure together the sole, the shank piece, and the heel-seat flange of the counter stiffener.

Figures 14 to 18 inclusive illustrate a shoe, 80 in the several steps of inserting the combined shank piece and counter stiffener in a turned shoe, tucking the lining in place and securing a heel.

Referring to the drawings, in Figures 1 85 to 6 inclusive I have illustrated, as previously indicated, the combined counter stiffener and shank piece and the manner which may be followed in making the same.

In Figure 1, I have illustrated a shank 90 piece blank at 20, which may be made of leather-board or other semi-flexible material, and it approximates in shape the sole of the shoe except that it is narrower and its heel end is designed to fit within the counter stiffener so as to overlap the heel-seat flange thereof and form the heel support for the heel portion of the wearer's 95 foot. This shank piece is long enough so as to extend approximately to the break in the sole at the point near the ball of the 100 foot. Its ends and side edges may be properly skived as indicated in Figure 2. This member is split from its heel end inwardly to a point 23 or line relatively near the front end of the shank piece, to provide two 105 members 21, 22, which are joined at about the point 23 in Figure 3, being thus integrally connected with the inner end of the body. The upper member 21 forms a flap 110 which may be bent at an angle to the lower end for a purpose to be described. 24 represents a shank stiffener which is prefer-

ably made of metal and is molded into the desired curvature lengthwise and transversely as may be desired. This is attached to the shank piece by tacks, staples or other convenient forms of fastenings indicated at 5 25, 26, 26, so as to underlie both the lower member 22 and the unslit front end of the shank piece. These fastenings are illustrated in the form of tacks, and those at 26, 10 26 are driven through and clinched in the member 22 so as to leave the member 21 free. The counter stiffener 27 is likewise made of leather-board or other suitable material, and it is initially molded to the desired shape. It is provided with the upstanding walls and with a heel-seat flange 28. When these two elements have been thus formed, they are assembled so that the heel portion of the counter stiffener extends into 15 20 and lies upon the heel-seat flange of the counter stiffener, and so that it occupies the area defined by the upstanding walls of the counter stiffener; and the lower member 22 of the shank piece is attached to the heel-seat flange by several staples or other fastenings indicated at 29. When this has been accomplished, it will be seen that I have now provided a combined shank piece and counter stiffener which constitute an entity 25 30 or article of manufacture and which may be sold as such for incorporation in a turned shoe. If desired, the shank piece and the shank stiffener may be simultaneously molded prior to the attachment of the shank piece to the shank stiffener.

As I have previously stated, this combined shank piece and counter stiffener may be attached to a partially formed shoe before the latter is turned or after it is turned. 40 In the manufacture of turned shoes, it is customary to last the shoe inside-out, as illustrated, for example, in Figures 8 and 9, and then to turn the shoe after the last has been withdrawn therefrom. In Figure 45 8, I have shown how the combined shank piece and counter stiffener may be attached to the sole of the shoe prior to the turning operation. In this case, the combined elements may be placed upon the sole and it 50 may be tacked to the face thereof by a row of tacks 30 driven through the marginal portion of the member 22 and through the heel-seat flange of the counter stiffener into the sole. In such case, the last is then withdrawn from the shoe and the shoe is turned. 55 The counter is introduced between the upper and the lining, and the edges of the lining are formed into the reentrant angle formed by the counter stiffener, and the loose 60 ends of the lining are laid flat upon the surface of the member 22. Then the loose member or flap 21 of the shank piece is swung from the position shown in Figure 8 down so as to lie flat against the member 22 and 65 so as to clamp the loose edge of the lining

against the member 22. The loose member 21 may now be secured in place in any suitable way. For example, it may be fastened in place by a series of tacks or loose nails driven through its marginal portions 70 into the sole, or it may be secured in place, as shown in Figure 10, by the nails 31 when the heel 32 is secured to the shoe. In this case, the nails 31 penetrate the sole 33, the heel-seat flange of the counter stiffener, the two members 21 and 22 of the shank piece, and their ends are turned or clinched as illustrated.

Instead of primarily or initially fastening the combined counter stiffener in place upon the sole, before the shoe is turned, by a row or series of tacks 30, as illustrated in Figures 8 and 9, one or more tacks or other fastenings 34 may be driven through the member 22 into the sole, as shown in Figure 11; 80 and, after the shoe has been turned, the lining properly placed inside of the counter, and the member 21 turned down into place so that its marginal portions will rest upon the edges of the lining, the heel portion of 85 the shoe may be loose-nailed as shown in Figures 12 and 13, the nails in this case being indicated at 35. These loose nails or tacks may be driven either through the sole into the shank piece or vice versa. 90

If it be desired to first turn the shoe before the combined counter-stiffener shank piece is located, this may be easily accomplished. After the last has been withdrawn and the shoe has been turned, the lining at 100 the heel end of the shoe is drawn up so that it may be forced over the upstanding wall of the counter stiffener, and then folded down on the inside of said wall, as illustrated in Figures 14 and 15. This is accomplished after the combined shank piece and counter stiffener has been secured in place by one or more tacks, or the initial securing of the said combined element may be accomplished after the lining has 105 been forced down into place. After the lining has been properly folded down inside of the shank stiffener and its loose edge has been caused to lie flat on the face of the member 22, tacks may be driven through it 110 and through the member 22 and the heel-seat flange of the counter stiffener into the sole, as indicated in Figures 12 and 13, or several tacks may be passed through the middle portion of the member 22 to hold it 115 in place. Then the loose flap 21 of the shank piece is swung back and pressed down so as to lie upon the inturned marginal edge of the lining. The heel portion of the shoe may now be loose-nailed, as indicated in 120 Figures 12 and 13, or, when the heel is secured in place, the heel nails 31 may be forced through the sole, the edge of the upper, the heel-seat flange of the counter, the lining, and the marginal portion of the 125 130

shank piece including both members 21 and 22.

The inner end of the shank piece may be secured to the sole by any suitable means.

5 It may be cemented in place or it may be attached by one or more fastenings driven into the sole of the shoe. In any event, however, the inner end of the shank piece must be secured rigidly in place, after which the 10 shoe is completed by the insertion of the usual filler piece.

What I claim is:—

1. As a new article of manufacture, a counter stiffener and a shank piece, said 15 shank piece having its heel portion composed of an upper member and a lower member, said lower member being secured upon the heel-seat flange of the counter stiffener leaving the upper member loose, so that its 20 free end can be bent upwardly away from the lower member.

2. As a new article of manufacture, a counter stiffener, a shank piece and a shank 25 stiffener, the shank piece having at its rear end an upper member and a lower member, said lower member being secured to the heel-seat flange of the counter stiffener with the 30 upper member free at its rear end to bend upwardly and forwardly away from the counter stiffener, and the said shank stiffener being secured to the under face of said lower shank-piece member.

3. As a new article of manufacture, a combined counter stiffener and shank piece, said 35 shank piece having its heel portion split parallel to its face.

4. As a new article of manufacture, a combined counter stiffener and shank piece, comprising a molded counter stiffener, and 40 a shank piece fitting within the upstanding wall of said counter stiffener and permanently attached to the heel-seat flange thereof, said shank piece being split from its rear end to a line approximating the ends of the heel-seat flange and furnishing a flap.

45 5. A turn shoe comprising a sole, a lining, an upper, a counter stiffener, and a shank

piece, said shank piece having upper and lower members attached together at the forward ends thereof, the lower member being 50 secured to the heel-seat flange of the counter stiffener, and the edges of the shoe lining being located and secured between said members.

6. A turn shoe comprising a molded 55 counter stiffener, a shank piece, said shank piece being split from its heel end to furnish an upper and a lower flap, and means for attaching said lower flap upon the heel seat flange of the counter stiffener, the edges 60 or skirt of the counter lining being secured between said flaps of said shank piece.

7. A process of making a turn shoe, comprising assembling a molded counter stiffener and a shank stiffener split at its rear 65 end to provide an upper and a lower flap and having its lower flap secured to the heel-seat flange of said counter stiffener, and a lasted and stitched shoe, tucking the edge or skirt of the counter lining between the two 70 flaps of the shank piece, and fastening the parts together by fasteners passed into the said flaps, the heel-seat flange of the counter stiffener and the sole.

8. As a new article of manufacture, a flexible shank piece for use in a shoe additional to the sole thereof, said shank piece being split at its rear end to a point nearer its front 75 end than its rear end to form two members integrally connected at their front ends.

9. As a new article of manufacture, a shank piece for use in a shoe additional to the sole thereof, said shank piece being split at its rear end to a point nearer its front 85 end than its rear end to form two members integrally connected at their front ends, and a stiffener strip on the under face of the shank secured to the lower member and to unsplit front end of said shank piece. 90

In testimony whereof I have affixed my signature.

MILTON L. DODGE.
